(57) **CLAIM**

We claim the ornamental design for a gaming machine, as shown and described.

DESCRIPTION

FIG. 1 is a front perspective view of a gaming machine showing our new design;

FIG. 2 is a front view of the gaming machine shown in FIG. 1;

FIG. 3 is a back view of the gaming machine shown in FIG. 1;

FIG. 4 is a right side view of the gaming machine shown in FIG. 1;

FIG. 5 is a left side view of the gaming machine shown in FIG. 1;

FIG. 6 is a top view of the gaming machine shown in FIG. 1;

FIG. 7 is a bottom view of the gaming machine shown in FIG. 1;

FIG. 8 is a front perspective view of a gaming machine showing an alternative embodiment of our new design;

FIG. 9 is a front view of the gaming machine shown in FIG. 8;

FIG. 10 is a back view of the gaming machine shown in FIG. 8;

FIG. 11 is a right side view of the gaming machine shown in FIG. 8;

FIG. 12 is a left side view of the gaming machine shown in FIG. 8;

FIG. 13 is a top view of the gaming machine shown in FIGS. 8; and,

FIG. 14 is a bottom view of the gaming machine shown in FIG. 8.

The broken line showing of portions of the gaming machine depicts environment and forms no part of the claimed design.
